UNITED STATES PATENT OFFICE.

ARTHUR R. GRIFFES, OF WYOMING, OHIO, ASSIGNOR, BY MESNE ASSIGNMENTS, TO THE FLINTKOTE COMPANY, OF BOSTON, MASSACHUSETTS, A CORPORATION OF MASSACHUSETTS.

DISPLAY DEVICE.

Application filed July 29, 1926. Serial No. 125,817.

My invention relates to display devices which are adapted to illustrate the effect of various shades of roofing material with various colors and shades of house trim, and body color.

It has become possible, due to the wide varieties of colors of stained wooden shingles and mineral surfaced composition shingles, to obtain a roof of a color which will blend properly with the color and trim of a house or other building, and my invention is directed to the provision of a device whereby the purchaser can try out various colors of roofs with house colors, in order to satisfy himself as to the colored roof that he desires to purchase.

It is my object to provide for the dealers in roofing a framework for a miniature house, together with cards printed in colors which will show the front and sides of the house, and to so construct the framework and cards that the cards will slip into and out of the frame readily. In connection with the frame a suitable support is provided, and miniature sized roofs of miniature sample shingles are built so as to be set up quickly as a roof for the miniature sized house.

I attain my objects above detailed, by that certain structure and arrangement of parts to be hereinafter more specifically pointed out and claimed.

In the drawings:—

Figure 1 is a perspective view of a framework suitable for the purposes of my invention.

Figure 2 is a plan of a suitable card for the side of a house to fit such a frame.

Figure 3 is a front elevation of the complete assembly.

Figure 4 is a plan view of the device in knock down relation.

Figure 5 is a section along the lines 5—5 in Figure 3.

Figure 6 is a section along the lines 6—6 in Figure 1.

The device is formed of two end plates 1 and 2 made of sheet metal, and having an upwardly turned bottom flange 3, and a downwardly turned flange 4, at one upper corner (to the rear of the toy house). The forwardly inclined top edge is flanged inwardly at 5, with the flange 5 formed with an under curled portion 6 that forms a retainer for the upper roof support.

The forward vertical edges of the two side plates are each flanged and curled to form hinge leaf portions 7, and flanges or ears 8 may be turned in at the back to provide supports for bracing rods 9. The rods are, in the illustrated device, made of metal and hooked through holes 10 in the flanges 8, and they have terminal bent portions 11 to hook into the front lower frame.

The front of the device is formed of an upper and a lower sheet metal bar. The upper bar as shown at 12, has a downwardly turned flange 13 at the top, and hinged leaf curled ends 13^a to be aligned with the portions 7 of the side plates. Pintles 14 are dropped through the leaves so formed, and also through like leaves in the bottom front bar.

The bottom front bar is formed of a sheet metal strip 15 with an upwardly turned bottom flange 16 and curled ends 17 for hinge leaves to be engaged by the said pintles 14.

Cards 18 with sloping tops are provided, as shown in Figure 2, and printed in colors to indicate the side of a house. The card of whatever color desired is placed against the sheet metal side plate and engaged by the flanges 3 and 4 thereof. The same is done for the opposite side of the toy house.

The front cards 19, which are also color printed, are set into engagement with the flanges 13 and 16 of the front top and bottom bars.

A cross bar 20 is placed by sliding the same interengagement with the hooked under flange portions at the front upper edge of the side plates. The roof is formed with a deck 21 finished with shingles 22, of small size but of real roofing materials. The roof is shaped to fit with suitable eaves lying over the frame, and has a batten 23 to engage above the top cross bar, and if desired, a second batten 24 to engage the front card supporting arm.

The brace rods are hooked into holes in a rearwardly extended flange 25 in the bottom cross bar of the front of the frame.

By removing the braces, the whole device can be laid flat and packed up in a suitable carton for shipment, which carton, if desired, may also contain a set of cards. There will naturally be as many sets as desired of the cards, one front card and two side cards to a set, printed with harmonious colors.

Foliage cards may also be provided to increase the realism of the miniature house; no foliage cards are shown as they may be of any desired shape and color.

5 There will also be a series of roofs, finished in different colors or mixed colors, with toy sized shingles of real roofing material, such as it is desired to sell to the customer.

Thus by removing and setting up cards 10 showing various colors, and trying the cards out with roofs of different colors, the purchaser can, in miniature, see a house in which the actual colors he might have, are set in exactly the right relation for him to judge 15 what he likes as a color for his roof, to blend with the color which he has his house or may wish to select for his house.

It will naturally be possible to accomplish 20 my objects without following the type of structure forming the card and roof supporting frame, of which the essentials are a shape to suit the cards, and means for detachably engaging the cards in erected position and retaining a miniature sized roof in 25 proper relation to the simulation of a house formed by the cards.

Having thus described my invention what

I claim as new and desire to secure by Letters Patent is:—

1. A device for displaying roofing material comprising a frame support, elements simulating the appearance of portions of a building with the frame support having means for engaging said elements, and a roof member, adapted to be set on the frame support in the same relative relation to said elements as would appear in an actual house, said frame support consisting of a series of 30 articulated sections adapted to fold up for shipment in a flat container. 40

2. A device for displaying roofing material comprising a frame support, elements simulating the appearance of portions of a building with the frame support having means for engaging said elements, and a roof member, adapted to be set on the frame support in the same relative relation to said elements as would appear in an actual house, said frame support consisting of a series of 45 articulated sections adapted to fold up for shipment in a flat container, and pivoted arms for bracing said sections in set up position. 50

ARTHUR R. GRIFFES.
